UNITED STATES PATENT OFFICE.

HENRY J. GAISMAN, OF NEW YORK, N. Y., ASSIGNOR TO AUTO STROP COMPANY, OF NEW YORK, N. Y., A CORPORATION OF NEW YORK.

RAZOR.

1,039,377.

Specification of Letters Patent. Patented Sept. 24, 1912.

Application filed October 25, 1909. Serial No. 524,330.

To all whom it may concern:

Be it known that I, HENRY J. GAISMAN, a citizen of the United States, and resident of New York city, borough of Manhattan, in the county of New York and State of New York, have invented certain new and useful Improvements in Razors, of which the following is a specification.

My invention relates to improvements in the class of razors used in the manner of an ordinary razor having the shank extending in the direction of the edge of the blade, and the objects of my invention are to enable a thin blade to be detachably supported in connection with a guard; to enable the guard to have limited swinging movement with respect to the blade edge during use; to enable a double edged blade to be used, and the guard adjusted with respect to either edge as required; to protect the rear edge of a double edged blade to prevent injury to the user, while the opposite edge is being used; to enable the blade to be held with its cutting edge or edges away from the guard, while the razor is being cleaned or stropped, and to provide a razor which will be efficient in use and convenient in operation.

My invention comprises novel details of improvement and arrangements of parts that will be more fully hereinafter set forth and then pointed out in the claims.

Reference is to be had to the accompanying drawings forming part hereof, wherein,

Figure 1 is a side view of a razor embodying my invention; Fig. 2 is an edge view thereof; Fig. 3 is a detail perspective view; Fig. 4 is an end view; Fig. 5 is a section on the line 5, 5, in Fig. 3; Fig. 6 is an enlarged broken partly sectional side view; Fig. 7 is a section on the line 7, 7, in Fig. 3, and Fig. 8 is a fragmentary view.

Similar numerals of reference indicate corresponding parts in the several views.

At 1, 2 are plates movably connected together at one end, as by a suitable hinge 3, and adapted to clamp between them a suitable blade 4, such as a double edge relatively thin blade. To one of the plates, as the plate 1, at one end is attached a suitable shank 5, which may be pivotally connected with a suitable handle 6. At the end opposite shank 5 plate 1 is provided with a projection or stud 7. Plate 1 is provided with pins or studs 8 suitably spaced apart and

adapted to pass through suitable openings 4^a in blade 4, and plate 2 is provided with openings 2^a to receive the pins or studs 8, whereby the blade is detachably clamped in position between plates 1 and 2. Said plates 60 are maintained in clamping relation by any suitable means, such as by the frictional engagement of studs 8 with plate 2 at the openings 2^a, or by the spring-like action of the parts.

At 10 is a guard frame journaled upon shank 5 and stud 7, and adapted to inclose the blade along and around its edges and ends. Said frame is shown provided with a sleeve 11 rotatively mounted upon shank 70 5 and with a sleeve 12 at the opposite end rotatively mounted upon stud 7. One of the longitudinal bars or parts 10^a of the guard frame constitutes the guard for the blade edge, and the comb teeth 10^b of the 75 guard may be produced by suitably stamping the metal of the bar. The bar 10^a of the guard frame is made relatively wide to project on opposite sides of the adjacent blade edge to guard and protect the latter, (see 80 Fig. 5). Guard frame 10 is permitted limited lateral swinging movement in use with respect to the blade edge, and is also adapted to be maintained out of correlation with the blade edge to permit ready cleaning of the 85 razor. To this end stud 7 is provided with suitably disposed spaced teeth or projections 7^a which may be formed by making cuts or recesses 7^b in the end of the stud at right angles to each other, and sleeve 12 90 is provided with a transverse pin or bar 12^a adapted to fit in one or the other transverse recesses 7^b, whereby the corresponding projections 7^a will maintain the guard frame in the positions to which it may be turned. 95 In order that the guard 10^a may swing a limited distance with respect to the blade edge during shaving the recesses 7^b are sufficiently wide to permit cross bar 12^a to have freedom of movement or play between 100 the corresponding pairs of projections 7^a. To retain guard frame 10 in the desired position I provide a spring 13, shown coiled around shank 5 and bearing at one end against the outer wall 11^a of sleeve 11, and 105 at its opposite end said spring bears against plate 1 (see Fig. 6), thereby serving to maintain cross bar 12^a in the corresponding cross recess 7^b of stud 7. The corners of the blade when used in shaving may be further pro- 110

tected by clips 14 having ears 14^a adapted to extend along opposite sides of the guard frame to conceal and protect the corners of the blade, which clips are shown pivotally supported at 15 upon frame 10, and are adapted to swing toward and away from the corners of the blade in the direction of the blade.

When the parts are assembled as shown in Fig. 1 the razor may be used for shaving in the manner of an ordinary razor equipped with a guard, and when the blade edge is applied to the face the guard will swing sidewise sufficiently to permit proper shaving. By the arrangement shown the blade may be used from either side, as the guard may swing to either side of the blade edge, and the part 10^c of the guard frame will protect the rear edge of the blade when a double edged blade is used. When it is desired to clean the razor or to strop the edges of the blade, frame 10 is pushed or slid in an outward direction to release the cross pin or bar 12^a from stud 7, the frame 10 is then swung at right angles to the blade and released, whereupon the cross pin or bar 12^a will enter the corresponding cross recess 7^b of stud 7 and maintain the guard frame at right angles to the blade, as illustrated in Fig. 4. The guard frame may be swung half way around in the manner described to transfer the guard 10^a from one edge of the blade to the other. Blades may be removed and replaced without interfering with frame 10 while it is in the position shown in Fig. 3.

Changes may be made in the details of construction shown and described, within the scope of the appended claims, without departing from the spirit of the invention.

Having now described my invention what I claim is:

1. In a razor, a blade carrying holder, a guard for the edge of the blade, means for rotatably mounting the blade carrying holder and guard together, said means permitting endwise movement of one with relation to the other, means for limiting rotary motion of one member with relation to the other, means operated by said endwise movement for holding one member at an angle with relation to the other, and means for yieldably retaining the last mentioned means in operative position.

2. In a razor, a blade carrying holder, a guard for the edge of the blade, means for rotatably mounting the blade carrying holder and guard together, said means permitting endwise movement of one with relation to the other, means for limiting rotary motion of one member with relation to the other, means operated by said endwise movement for holding one member at an angle with relation to the other, means for yieldably retaining the last mentioned means in operative position, and clips hinged to

the guard and adapted to embrace the corners of said guard to protect the corners of the blade.

3. In a razor, a blade carrying member having studs thereon, a guard for the edge of the blade having sleeves at the ends thereof in which the studs are trunnioned, stop lugs spaced apart on one of the studs, means carried by one of the sleeves extending between the stop lugs and adapted to engage the said lugs to limit the movement of the guard with relation to the blade carrying member, a spring bearing against the blade carrying member in the opposite sleeve, and the end of said sleeve for retaining the lugs and member in operative relation, the said blade carrying member being of less length than the length of the frame to permit movement axially of the said studs whereby the lugs are disengaged from the said means carried by one of the sleeves.

4. In a razor, a blade carrying member having studs thereon, a guard for the edge of the blade having sleeves at the ends thereof in which the studs are trunnioned, stop lugs spaced apart on one of the studs, means carried by one of the sleeves extending between the stop lugs and adapted to engage the said lugs to limit the movement of the guard with relation to the blade carrying member, a spring bearing against the blade carrying member in the opposite sleeve and the end of said sleeve for retaining the lugs and member in operative relation, the said blade carrying member being of less length than the length of the frame to permit movement axially of the said studs whereby the lugs are disengaged from the said means carried by one of the sleeves, said lugs also comprising means whereby the blade is held out of operative relation to the guard.

5. In a razor, a blade carrying member, studs thereon, a guard for a razor edge, sleeves on the said guard in which the studs are rotatable and in which they are movable axially, a spring in one of the sleeves bearing against the blade carrying member and the end of the sleeve for forcing the blade carrying member outwardly with relation to the spring, lugs spaced apart on the opposite stud, a member projecting from the sleeve into a space between the lugs, the relation of said member to the space being such that slight rotary motion is permitted the studs whereby the guard may be oscillated with relation to the blade.

6. In a razor, a blade carrying member, studs thereon, a guard for a razor edge, sleeves on the said guard in which the studs are rotatable and in which they are movable axially, a spring in one of the sleeves bearing against the blade carrying member and the end of the sleeve for forcing the blade carrying member outwardly with re-

lation to the spring, lugs spaced apart on the end of one of the studs, a member projecting from the sleeve and adapted to engage the said lugs for limiting the movement of the guard with relation to the blade and for holding the blade carrying member at an angle with relation to the said guard.

Signed at New York city, in the county of New York, and State of New York this 21st day of October, A. D. 1909.

HENRY J. GAISMAN.
